PATENTED AUG. 15, 1905.

B. H. TRIPP.
CORN HARVESTER.

APPLICATION FILED NOV. 14, 1904.

2 SHEETS—SHEET 2.

UNITED STATES PATENT OFFICE.

BRADFORD H. TRIPP, OF REMSEN, IOWA, ASSIGNOR OF ONE-HALF TO
JOHN HOLTGREWE, OF REMSEN, IOWA.

CORN-HARVESTER.

No. 797,157. -

Specification of Letters Patent.

Patented Aug. 15, 1905.

Application filed November 14, 1904. Serial No. 232,731.

To all whom it may concern:

Be it known that I, BRADFORD H. TRIPP, a citizen of the United States, residing at Remsen, in the county of Plymouth and State of Iowa, have invented a new and useful Corn-Harvester, of which the following is a specification.

This invention relates to corn gathering or harvesting devices of the class which are equipped with means for snapping the ears from the stalks, means for conveying the ears to a husking device, and means for depriving the ears of the husks, and for finally delivering the ears into a receptacle.

The invention has for its object to provide a machine of the class referred to which shall possess superior advantages in point of simplicity, durability, and general efficiency.

With these and other ends in view, which will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of embodiment of the invention, it being, however, understood that no limitation is necessarily made to the precise structural features therein exhibited, but that the right is reserved to any changes, alterations, and modifications to which recourse may be had within the scope of the invention and without departing from the spirit or sacrificing the efficiency of the same.

In said drawings, Figure 1 is a top plan view of a corn-harvester constructed in accordance with the principles of the invention. Fig. 2 is a sectional elevation of the same. Fig. 3 is a sectional elevation taken on the line 3 3 of Fig. 1. Fig. 4 is a sectional view taken on the line 4 4 in Fig. 1. Fig. 5 is a plan view showing the snapping-rollers and the supporting and driving means for the same. Fig. 6 is a sectional detail view taken through the elevating and husking device and exhibiting a pair of the husking-rollers.

Corresponding parts in the several figures are indicated by like characters of reference.

The main frame of the improved machine is composed of the outer and inner side beams 1 2, which are suitably connected by means of cross-pieces 3 3, which are laterally extend-

ed to support the gathering-frame F. Said side pieces are also connected at their front ends by a cross-piece 4. The side pieces of the frame are supported intermediate of their ends upon an axle 5, upon the ends of which the outer and inner traction-wheels 6 and 7 are journaled. The front end of the frame is supported upon a truck, including an axle 8 and supporting-wheels 9, said truck being connected with the front cross-piece 4 by means of a swivel or king bolt 10. The frame-pieces 1 2 support uprights 11, the upper ends of which are connected by cap-beams 12 and 12^b, which are extended laterally above the extensions of the cross-pieces 3 3 and which assist in supporting the gathering-frame F.

The gathering-frame comprises the lower corn-guides 14 15 and the upper corn-guides 16 17, which latter, in addition to being supported by the cap-beams or cross-pieces 12 12^b, are supported and reinforced by means of a yoke 18, connected with an upright 19, rising from the frame-piece 2. The front end of the lower inner corn-guide 15 is supported by one of the cross-bars 3 of the frame. The lower corn-guides 14 and 15 are provided at their front ends with forwardly-extending gathering-fingers 20 for the purpose of picking up down corn and guiding it between the conveying members, which will be presently described.

The lower corn-guides 14 15 are provided upon their inner sides with recesses 21 for the accommodation of the snapping-rolls 22, the shafts of which are journaled at their front ends in said corn-guides and at their rear ends in one of the cross-pieces 3.

The outer upper corn-guide 16 is provided near its front and rear ends with slots 24, affording bearings for laterally-slidable boxes 25. Pivotaly mounted upon the lower outer corn-guide 14, near the front and rear ends of the latter, are arms 23, the free ends of which have boxes or bearings 26 26, in which are journaled the lower ends of shafts 27, the upper ends of which are journaled in the boxes 25. The shafts 27 carry the drums or cylinders 28. Springs 29 are suitably arranged to force the several shaft-supports in an inward direction. The inner corn-guides 15 17 are provided with bearings for shafts 30, carrying drums or cylinders 31. The drums 28 and 31, which are approximately vertically disposed, serve to support endless

aprongs 32 33, each equipped with toothed slats 34 34 and coöperating to constitute an endless carrier. It will be seen that the shafts 27, carrying the drums 28, which support the outer apron 32, are capable of being forced in an outward direction against the tension of the springs 29, thus permitting the carrier to yield to the pressure of material passing between the members thereof.

The transporting-wheel or traction-wheel 7 carries a sprocket-wheel 35, which is connected by a chain 36 with a sprocket-wheel 37 upon a counter-shaft 38. The latter carries a bevel-gear 39, meshing with a bevel-gear 40, upon the lower end of the rear drum-supporting shaft 30, which is thus driven. The upper end of said rear shaft 30 carries a sprocket-wheel 41, which is connected by a chain 42 with a sprocket-wheel 43 upon a stub-shaft 44, which is mounted in the box 25, which supports the upper end of the rear shaft 27. Said rear shaft 27 carries a pinion 45, meshing with a pinion 46 upon the stub-shaft 44. A spring-actuated chain-tightener 47 is provided to keep the chain 42 taut. It will be seen that by this mechanism motion is transmitted in the proper direction from the rear shaft 30 to the rear shaft 27 without interfering with the flexibility of the supporting means for said shaft.

The outer transporting-wheel 6 carries a sprocket-wheel 46, which is connected by a chain 47 with the sprocket-wheel 48 upon a counter-shaft 49, having a bevel-pinion 50, meshing with a bevel-pinion 51 upon the shaft of one of the snapping-rolls, which is thereby driven. The shafts of the snapping-rolls are also provided with intermeshing pinions 52, whereby both of said rolls are driven in the proper direction.

Under the rear or discharge ends of the aprons 32 33 is disposed a chute 53, discharging into the lower end of the trough 54 of the elevator 55. Said elevator-trough is supported at the rear end of the frame of the machine and is provided near its lower and upper ends with bearings for the shafts 56 57, supporting the wheels or drums upon which the endless carrier 58 of the elevator is mounted, said endless carrier being equipped with a plurality of slats 59. The shaft 57 carries a pinion 60, meshing with an idle pinion 61, with which is connected a sprocket-wheel 62, connected by a chain 63 with a sprocket-wheel 64 upon a suitably-supported shaft 65, carrying a bevel-pinion 66, which meshes with a bevel-pinion 67 upon the driven shaft 38, from which motion is thus transmitted to the carrier of the elevator.

The bottom of the elevator-trough is composed in part of a series of husking-rolls 68 69, which are mounted in pairs in the sides of the elevator-trough. The shafts 70 of the lower husking-rolls of the several sets are provided at their front ends with sprocket-wheels 71,

and the shafts 72 of the upper husking-rolls of the several sets are in like manner provided at their rear ends with sprocket-wheels 73. The ends of the several shafts which are unprovided with sprocket-wheels are mounted slidably in slots 74 in the sides of the trough or casing, and springs 75 are provided whereby the free ends of the shafts will be forced in the direction of the opposite shafts. By this construction it will be seen that each pair of rolls is mounted yieldably in such a manner as to permit the husks torn from the ears of corn to pass between said rolls and to be discharged upon the ground. Each of the husking-rolls is provided with one or more annular grooves 76 and with radially-projecting pins 77 engaging the annular groove or grooves of the mate thereof. The sprocket-wheels 73 of the upper husking-rolls of the several sets are driven by a chain 78 passing over a sprocket-wheel 79 upon the upper elevator-shaft 57. The sprocket-wheels 71 of the lower husking-rolls of the several sets are driven by a chain 80 passing over a sprocket wheel 81 upon the shaft 65. The husking-rolls of each pair will thus be driven in the proper direction reversely to each other.

Chain-tighteners 82 and 83 are provided for the purpose of keeping the chains 78 and 80 sufficiently taut to drive the several rolls.

The elevator trough or casing is provided at its upper end with a discharge-spout adapted to discharge the husked corn into a wagon or receptacle which may be driven alongside of the machine.

The operation of this invention is as follows: The machine is driven along the field in such a manner that the stalks of corn will enter between the corn-guides and between the approximately vertical aprons 32 and 33, down corn being elevated and guided between the carrier-aprons by means of the fingers 20. The snapping-rolls below the carrier-aprons are placed sufficiently low to engage the stalks below the lower ears. As soon as the stalks pass into engagement with the snapping-rolls they will be buckled down by the latter until the ears are encountered, the ears being readily snapped off by the combined action of the snapping-rolls and the carrier-aprons, between which they are held. The stalks will pass downwardly and out of the way between the snapping-rolls, while the ears are carried in a rearward direction between the aprons 32 and 33 and are deposited upon the chute 53, whereby they are guided into the trough or casing of the elevator, where they are seized upon by the elevator-buckets and carried in an upward direction over the bottom of the elevator-casing. Presently the ears will be engaged by the husking-rolls, the teeth of which will tear and loosen the husks, which will pass downwardly between the rolls, being thereby stripped and torn from the ears. If the husking opera-

tion is not fully performed by the first pair of husking-rolls, it will be unfailingly performed by one of the succeeding sets or pairs of rolls. The husks will pass between the rolls and drop upon the ground, while the ears will be carried upwardly and discharged at the upper end of the elevator.

Having thus described the invention, what is claimed is—

1. A pair of stalk-engaging snapping-rolls and a pair of endless aprons supported adjacent to said rolls and coöperating to form an ear-engaging carrier, shafts and drums supporting the endless aprons, and yieldable supporting means for the shafts of one of the aprons.

2. In a machine of the class described, a frame, cross-pieces upon said frame extended laterally to form supporting-brackets, pairs of corn-guides supported upon the said brackets, corn-engaging snapping-rolls supported adjacent to the inner sides of the lower corn-guides, shafts journaled in the lower and upper corn-guides, drums upon said shafts, endless aprons mounted upon said drums and coöperating to constitute an ear-engaging carrier, and operating means.

3. In a machine of the class described, a frame having cross-pieces extended laterally to form supporting-brackets, corn-guides

supported upon said brackets and having recesses in their inner sides, and corn-engaging snapping-rolls disposed in said recesses and having shafts journaled at their front ends in the corn-guides and at their rear ends in a supporting-bracket.

4. In a machine of the class described, a frame having cross-pieces extended laterally to form supporting-brackets, uprights upon said frame, laterally-extended cap-beams, upper corn-guides supported by said cap-beams, lower corn-guides supported upon the laterally-extending supporting-brackets, an upright mounted upon the frame and having a yoke supporting the front ends of the upper corn-guides, stalk-engaging snapping-rolls supported adjacent to the inner sides of the lower corn-guides, shafts journaled in the lower and upper corn-guides, drums upon said shafts, endless aprons upon said drums coöperating to constitute an endless ear-engaging carrier, and operating means.

In testimony that I claim the foregoing as my own I have hereto affixed my signature in the presence of two witnesses.

BRADFORD H. TRIPP.
